UNITED STATES PATENT OFFICE.

JOSEPH CLAYTON, OF NEW YORK, N. Y.

SMOKER'S PIPE.

Application filed November 2, 1923. Serial No. 672,367.

The present invention relates to improvements in smokers' articles and is more especially directed to a tobacco pipe.

As is well known, various attempts have been made to provide a pipe for smoking tobacco which would be of a construction to prevent the entrance of particles of tobacco or nicotine into the stem or mouthpiece, from which they may be drawn into the mouth of the smoker. These efforts to overcome the objectionable features, which are inherent to pipe smoking, have been largely unsuccessful by reason of the fact that the structures which were evolved were more or less complicated, so that the cost of production rendered the manufacture and marketing of the articles unprofitable.

The primary object of the present invention is to provide a pipe for smoking tobacco which is of a simple construction, so that it may be economically produced, and which embodies a structure which will positively prevent the introduction of particles of tobacco and nicotine laden moisture into the mouthpiece or stem of the pipe, and will, in addition, insure a perfect draft and a cool and refreshing smoke. My invention further contemplates a smoker's pipe having the aforesaid characteristics and advantages which may be readily cleaned, so that it may at all times be maintained at its highest efficiency, in carrying out the objects of my invention, and thereby overcoming the extremely objectionable features which are now present in pipe smoking.

Other objects and advantages of my invention will present themselves as the description proceeds, and I would have it understood that I reserve unto myself all rights to the full range of equivalents, both in structure and use, to which I may be entitled under my invention in its broadest aspect.

For the purposes of the present disclosure, I have illustrated a preferred embodiment of my invention, but my invention may take other forms without departing from the spirit and scope thereof as defined by the appended claim.

In the drawings:

Fig. 1 is a longitudinal section of a smoker's pipe, made in accordance with my invention; and

Fig. 2 is a view partly in section on the line 2—2 of Fig. 1.

Referring now to the drawings in detail, in which like characters of reference are employed to designate similar parts in each of the two views, 7 indicates the bowl of the pipe having a stem 8 which may be formed integral therewith, as shown, or may be detachable therefrom, in accordance with the standard practice followed in pipe construction.

It will be observed that the bowl 7, which is preferably of a cylindrical shape, is open at its lower end, and is provided with a cap or closure 9, having a flange or rim 10, adapted for threaded engagement with the inner wall of the bowl, as shown at 11.

The stem 8 is formed with the usual smoke passage or duct 8^a which communicates with the chamber or passage 12 formed by the spaced partitions 13 and 14, 75 located within the bowl adjacent to the point at which the stem 8 is connected to the latter.

In the production of a pipe, in accordance with my invention, it will be manifest that a block from which the bowl is to be made may be drilled the requisite distances from the top and bottom to provide the tobacco chamber 7^a and the collecting chamber 7^b, the partition 13 forming the base of the former, while the partition 14 forms the top of the latter. A longitudinal drilling through the stem 8, continued into the solid portion remaining between chamber 7^a and 7^b, will result in the formation of the aforesaid partitions, and provide a smoke duct or passage, as clearly shown in Fig. 2, or, if desired, the space between the partitions may be enlarged to provide a chamber, such as heretofore described.

Following the formation of the partitions 13 and 14, each of them is apertured as shown at 15 and 16, the apertures of each set, it will be noted, being in alinement with those of the other set.

The outer end of the stem 8 may be threaded or otherwise formed to receive the usual mouthpiece 17, so that the latter may be readily removed for the purpose of facilitating cleaning of the pipe, when that is found necessary.

It will be evident from the description of my invention that, when the tobacco

2
chamber 7^a is filled with tobacco and the tobacco ignited, combustion may be readily maintained by the air passing through the tobacco in the usual manner, the smoke being drawn through the openings 15 in the partition 13 and out through the stem 8 and mouthpiece 17. Any moisture or products of combustion which percolate through the openings 15, instead of being drawn into the stem 8, will drop or fall through the openings 16 in the partition 14 and into the collection chamber 7^b. Thus the user is assured that, particles of tobacco and the nicotine laden moisture which are heavier than smoke, will not find their way into the stem 8 so that a clean cool smoke will result.

When it is desired to clean the pipe, it is evident that the relatively large smoke passage within the stem 8 and the communicating duct formed by the partitions 13 and 14 may be quickly cleaned, as well as the aligned openings 15 and 16, the removal of the plug or cap 9 facilitating the cleaning operation of these parts, and also permitting a thorough cleansing of the collection chamber.

What is claimed is:

A smoking pipe including an integral bowl structure of substantially cylindrical shape and having three inter-communicating compartments; the uppermost of said compartments constituting the bowl chamber proper and being a cylindrical well having its axis substantially parallel to the axis of the bowl structure, the lowermost of said compartments constituting a refuse collector and being a cylindrical well having its axis substantially parallel to the first-mentioned well, and the intermediate compartment constituting a smoke draft chamber for serving the stem of the pipe and being a cylindrical passage having its axis substantially perpendicular to the above-mentioned axes, each of the wells having cylindrical ports in its bottom wall, said ports placing in communication said wells and said passage, the said ports being arranged in aligned pairs; whereby ordinary drilling operations are solely required to form the two wells, the passage, said ports, and all the interior partitions of the integral bowl structure.

JOSEPH CLAYTON.
